UNITED STATES PATENT OFFICE

2,288,558

FRICITION WINDOW SASH MOUNTING

Fred N. Vose, Belfast, Maine, assignor to
 Mathews Brother Co., Belfast, Maine, a corpora-
 tion of Maine

Application November 28, 1939, Serial No. 306,449

2 Claims. (Cl. 20—52)

This invention relates to window construction wherein the sashes are held frictionally instead of being counterbalanced. For this purpose the window casing is provided with sash-engaging strips pressed into frictional engagement with the edges of the sashes. The heavier the sash for a given length of engaging strip contacted, or the shorter the engaging strip contact for a given weight of sash, the greater is the frictional pressure required to maintain the sash in lifted position, but a pressure greater than necessary to hold the sash in any position in which it may be placed is not desirable since it adds to the effort necessary to move the sash. Heretofore it has been the usual practice to provide for the pressure required in any particular installation by selection of the size and stiffness of the springs which have been employed to press the friction strips against the sashes. This method is largely a matter of guess work and many times requires trial and change for reasonably satisfactory operation.

An object of the present invention, therefore, is to provide for adjustability of the spring pressure in such a manner that the adjustment may be made after assembly of all the parts and in accordance with the individual requirement of each sash.

A further object is to provide for such adjustment which shall be effective over a substantial length of the friction strip, rather than merely locally, so that the effects on the sash may be made readily substantially uniform throughout the range of motion of the sash.

For a more complete understanding of this invention, reference may be had to the accompanying drawing in which—

Figure 1 is a vertical section through a window frame and related parts showing upper and lower sashes therein, this structure embodying the invention.

Figures 2 and 3 are detail sections to a larger scale on section lines 2—2 and 3—3, respectively, of Figure 1.

Figure 4 is a detail section on line 4—4 of Figure 3.

Figure 5 is a view similar to a portion of Figure 3, but illustrating adjustment of the frictional pressure on a window sash.

Referring to the drawing, at 1 and 2 are indicated the upper and lower sashes of a window which sashes are slidable within the sash guides 3 and 4, respectively. As shown, the sash guides are formed in part by a metallic strip 5 having a central sash separator portion 6 which may be of

substantially rectangular form, and between this and the end members 7 and 8 of the frame, the strip 5 is bent to form a lining portion 9 for a pair of grooves 10 positioned in the bases of the sash guide portions of the frame. Within each of these lining portions 9 there is mounted a friction sash-engaging member 15. This may well be formed of sheet metal bent to generally U form, so that its side portions 16 may engage between the sides of the lining portion 9 and its outwardly projecting intermediate wall portion 11, which is shown best in Figures 2 and 4, is made rounded and engages within a shallow rounded channel 18 in the edge portion of the sash. These members 15 are spring pressed against the edges of the sash and preferably extend the full lengths of the sash guides in order to act not only as friction elements for retaining the sashes in any positions of sliding adjustment, but also to act as weather strips, sealing the frame and sashes from passage of air therewith.

Each of the strip members 15 is shown as secured as at opposite ends within the frame recesses 10, and for this purpose a light coil spring 11 has been illustrated, one end portion 12 of which may be extended through a perforation 13 in the lining part 9, the opposite end of each of these springs being extended through a hole 14 in the strip portion 15 and hooked thereover as shown best in Figure 4. These springs act to retain the friction members within their recesses with possibility of yielding to an extent sufficient to insure engagement of the strip members on the sashes. These strip members are pressed outwardly against the sashes by the adjustable spring means shown best in Figures 3 and 5. Such a spring member comprises a leaf spring 20, opposite end portions of which are curved as at 21 and bear against one part, shown as the back face of the socket or the lining for this socket. Between these end portions 21 and the central portion 22, each spring member has an outwardly extending portion 23 which bears against the other part, shown as the back face of the friction strip member 15, the two portions 21 and 23 on each side of the central part of the spring acting to press the friction strip 15 outwardly. The extent of this outward pressure may be regulated as by turning the screw 25, which has a head 26 positioned in a depression 27 in the outer face of the friction strip 15, this screw engaging in a threaded opening 28 of a nut member 29 which may be secured to or be integral with the spring 20. As shown this nut member 29 is of rectangular shape so as to be held from rotation with

the screw, should it not be secured to the spring 20, by engagement with the opposite sides of the strip 15 within which it may be housed. By turning the screw 25 in a manner to bring the central portion of the spring 20 outwardly, the portions 23 and 24 are pressed with greater force between the inner face of the strip 1 and the back of the socket or the lining 10, to exert an increased effect to press the strip 15 out from its recess and into tighter frictional engagement with the edge of the sash contacted thereby. It will be noted that the head 26 of the screw is accessible on the inner face of the friction strip so that the adjustment of the spring tension may be made while the sash is in position. It may thus be adjusted to the conditions of the installation with respect to the length of the contact between the friction strip and the sash, and the weight of the sash, so that an accurate adjustment suited to the exact conditions of operation may be readily effected. It will be noted, also, that the adjustment is effective on the friction strip at two points spaced considerably from each other. Thus an adjustment over an extended length of the friction strip is produced instead of the effect being localized. For all but the very short sashes, ordinarily two of these adjustment springs will be all that is necessary for each friction strip, though for extremely high sashes, three may be used. Because of the extended area over which adjustment takes place, however, it is a relatively easy matter to provide for the desired frictional engagement of the sash substantially uniformly throughout its range of movement, so that the sash will remain in any position in which it is placed and yet will not slide too hard in any portion of its path.

In order to further provide for effecting weather stripping of the sashes, their parting strips 30 and 31 may be provided with inter-engaging weather strips 32 and 33, respectively, and suitable weather strips such as 34 and 35 may be provided for the lower edge of the inside sash and the top edge of the outside sash.

From the foregoing description of an embodiment of this invention, it should be evident to those skilled in the art that various changes and modifications might be made without departing from the spirit or scope of this invention as defined by the appended claims.

I claim:

1. The combination with a window frame having a sash guide, and a recess extending lengthwise within said sash guide, of a generally U shaped sash-engaging member seated in said recess, a leaf spring between the sides of said member and having end portions engaging the base of said recess and portions between said end portions and central portion for engagement with the back face of said sash-engaging member, and means engageable with the central portion of said spring and said sash-engaging member and accessible from the sash-engaging face of said member for adjusting said central portion toward and from the base of said recess, thereby adjusting the pressure of said spring acting to push said member against the edge of a sash movable in said sash guide.
2. The combination with a window frame having a sash guide, and a recess extending lengthwise within said sash guide, of a generally U shaped sash-engaging member seated in said recess, a leaf spring between the sides of said member and having end portions engaging the base of said recess and portions between said end portions and central portion for engagement with the back face of said sash-engaging member, the central portion of said spring being bowed away from said sash engaging member and having a threaded part operatively related thereto, and a screw engaging in said threaded part and having a head accessible from the sash-engaging face of said member.

CERTIFICATE OF CORRECTION.

Patent No. 2,288,558.

June 30, 1942.

FRED N. VOSE.

It is hereby certified that the name of the assignee in the above numbered patent was erroneously described and specified as "Mathews Brother Co." whereas said name should have been described and specified as --Mathews Brothers Co.--; and that the said Letters Patent should be read with this correction therein that the same may conform to the record of the case in the Patent Office.

Signed and sealed this 4th day of August, A. D. 1942.

(Seal)

Henry Van Arsdale,
Acting Commissioner of Patents.
